UNITED STATES PATENT OFFICE.

JOHN MUCKLE, OF KANSAS CITY, MISSOURI.

AIR-SHIP.

932,884.

Specification of Letters Patent. Patented Aug. 31, 1908.

Application filed July 8, 1908. Serial No. 441,761.

To all whom it may concern:

Be it known that I, JOHN MUCKLE, a citizen of the United States, residing at Kansas City, in the county of Jackson and State of Missouri, have invented a new and useful Air-Ship, of which the following is a specification.

My invention relates to and constitutes improvements in air-ships in which the form and construction of the air-ship are adapted to the means for lifting and propelling air-ships, herein specified, in which propelling lifting fans mounted on shafts and made to rotate by means of gearing and a motor, are placed fore and aft on both sides of the body of the air-ship, in such a manner that the rear fans do not track the front fans, and the paddles or blades of the fans dip below the floor plane of the air-ship, and in which devices are provided in the nature of compartments, in which the propeller-lifting fans are located, closed behind and above the fans and open in front and below to the free open air or in the form of a half cylinder or half barrel shaped device, secured to the air-ship, and in the hollow of which the upward and forward parts of the revolutions of the blades or paddles of the fans are made, and in which there are deflectors to deflect the air from the under side of the aero-plane to the exposed fronts of the fans, and in which there are also twin rudders, secured to the rear corners of the air-ship, for steering and stopping the air-ship, and in which vertical revolving paddle fans, which I term propeller-lifting fans, having their paddles or blades parallel to the shafts upon which the fans are mounted, mounted on shafts, turning in bearings, secured to the frame of the air-ship, are by means of gearing and a motor made to revolve clockwise, the point of view being toward the right side of the air-ship.

The objects of my invention are to provide a more substantial form of air-ship than such as have been in use, and a form adapted to the means herein specified for lifting and propelling air-ships, to provide an air-ship with the means of more effectively lifting and forcing it into the air and of keeping it up and propelling it in the air, and a better means for steering and stopping it than such as have been in use.

I attain these objects by the mechanism illustrated in the accompanying drawing, in which—

Figure 1 is a vertical elevation of the right side of an air-ship mounted on wheels, the stay ropes between the aeroplane and the bottom and top of the air-ship being omitted, and sections of the fore and aft ends of the aeroplane, or of the fore and aft wings of the aero-plane being omitted and showing, among other things, how the body of the air-ship is divided, from front to rear, into front, middle and rear sections, the dip of the fan blades or paddles below the floor plane of the air-ship, end views of the front and rear fans, mounted on the front and rear shafts, the chain belt gearing, the deflectors, the right rudder, the stem or prow of the air-ship, and the half cylinders or half barrel shaped devices, within the hollows of which the fan blades make the upward and forward part of their revolutions. The arrows point the direction the fans rotate. Fig. 2 is a sectional view of the lower part of the air-ship from the plane represented by the broken line 33 in Fig. 1, the stay ropes from the aero-plane to the bottom of the air-ship being omitted, and showing among other things how the air-ship is divided into front, middle and rear sections, and into five cross-sections, the positions of the front and rear fans, and of the shafts upon which they are mounted, the ball bearings in which the shafts turn, the chain belt gearing, the twin rudders, the stem or prow, and the floor of the air-ship partly cut away, showing the location of the motor. Fig. 3 is a vertical front elevation of the air-ship, omitting end sections of the side wings of the aeroplane, and showing among other things the prow, the front and rear deflectors, the dip of the paddles of the fans below the floor plane, the substructure carrying the ground wheels, the motor and the transverse bar with a wheel free to revolve on each end of it. Fig. 4 is a vertical right side elevation of a part of the front section of the body of the air-ship, showing among other things an end view of the front propeller-lifting fans, mounted on and keyed to the front shaft, the dead center belt of the fans, the half cylinder or half barrel shaped device, a part of the front deflector, and a section of the aeroplane with canvas

stretched on the under and upper sides of its framework. Fig. 5 is a detail of the propeller lifting fans. Fig. 6 is the aeroplane viewed from above.

5 Similar reference numerals refer to similar parts throughout the several views.

The aeroplane 1 and the body of the airship 2 constitute the air-ship. The air-ship may be mounted on wheels, on skids or on a 10 boat. The body of the air-ship includes the trestlework top 3 and the substructure 4. The body of the air-ship is divided into front 69, middle 70 and rear 71 sections and into five cross-sections, referred to from 15 right to left by the numerals 80, 76, 75, 74, 82 in Fig. 3.

The longitudinal stringers 31, 31, the transverse stringers 32, 33 and the ribs 33, 33 constitute the frame of the aeroplane. 20 The transverse stringers 32, 32 are bars of wood extended along and beyond and on both sides of and secured to the posts 34, 34; and the longitudinal stringers 31, 31 are laid upon the transverse stringers 32, 32 and are 25 bars of wood extended along and beyond and on both sides of and secured to the posts 34, 34. The transverse stringers 33, 33 are bars of wood secured above and below the stringers 31, 31, and to them. The ribs 33, 33 are 30 bars of wood across the upper and under sides of the stringers 32, 32 and secured by bolts and nuts to the stringers 33, 33; and said ribs and transverse stringers 32, 32 are 35 secured together at their intersections with ropes or wires. The horizontal stay ropes are secured to the ends of said stringers. Canvas is stretched under and over and secured to the frame of the aeroplane, including the stay ropes 49, 49. Stay ropes 41, 41 40 are secured at the intersections of the ribs and stringers of the aeroplane and to the bottom and top of the body of the air-ship. The aeroplane may be extended on the fore and aft wings and on the right and left 45 wings in sections joined together by means of "fishing the beam" joints secured with bolts and nuts, so as to make it easy to take the sections apart and put them together again.

50 The posts 34, 34, the longitudinal sills 55, 55, the transverse sills or tie beams 56, 56, the longitudinal stringers 31, 31, the transverse stringers 32, 32, the uprights 19, 19, the deflector posts 47, 47, the deflector braces 55 78, 79, the substructure frame 67 and braces which may be put in across the corners constitute the frame of the body of the air-ship (2). The stringers 31, 31 and 32, 32 constitute the roof timbers of the body of the air-ship. To give the body of the air-ship greater strength and stability as many wires 28, 28 as may be considered necessary may be 60 bound horizontally around the middle, 70, and rear, 71, sections and around the front section 69 and vertically around the body of 65

the air-ship, exclusive of the substructure and trestlework top.

The motor 8 is secured to the frame 67 of the substructure 4; three sprocket wheels 10 are secured on the drive shaft 9.

70 The wheel 5 and the sprocket wheel 65 are secured together and to the axle 64 which revolves in ball bearings secured in the frame 67. The chain belt 11 runs over the sprocket wheel 65 and over one of the three 75 sprocket wheels 10 on the shaft of the motor. The ground steering wheel 6, on a lower plane with respect to the frame 67 than the wheel 5 is, revolves on ball bearings on the axle 63 secured in the fork 61 which turns 80 in the head 60 which is secured to the frame 67. The handle bar 14 secured by means of the joint 62 to the fork 61 passes up through an opening in the floor 57 to the operator's 85 position 68 in the cross-section 75. The air-ship may be started on the ground on the wheels 5, 6, and steered while on the ground by means of the steering wheel 6 and the handle bar 14.

90 The transverse bar 40 carrying the wheels 7, 7 which are free to revolve on journals on the ends of said bar, and kept on by threads and nuts on the ends of said bar, is secured to the frame 67 of the substructure 4, and serves to keep the air-ship when at rest or 95 in motion on the ground from tipping side- wise too far.

95 The twin rudders 15, 15 are provided with 100 hinges 72, 72' upon which they turn and which are secured vertically to the rear corners of the body of the air-ship. Said rudders are controlled by the rudder ropes 16 secured to the rudders and which pass on the outside of the air-ship, over roller guides 66 secured to the air-ship, to the 105 middle section 70 and across it to the operator's position 68, and by the rudder ropes 16' which pass over roller guides 66' along the rear of the air-ship to the central cross- section, 75, then to the operator's position 68. 110 The rudder ropes may be secured by means of cleats 58 fastened to the floor 57.

115 The triangular prow or stem 27 is secured to the front part of the frames on the sides of cross-section 75, and is covered with canvas or other suitable materials.

120 The uprights 19, 19 may each be made of two timbers, secured together with bolts supplied with threads and nuts 20, 20, clamping the ball bearings 38, 38 between them and secured to the stringers 31, 31, and to the sills 55, 55. The annular ball bearings 38, 38, are let into mortises in the uprights 19, 19, and clamped with the bolts and nuts 20, 20. The shafts 36, 37, turn in the ball 125 bearings 38, 38 and carry thrust ball bearings 39, 39, on their ends, which are kept on and in place by means of the threads on the ends of the shafts and nuts 73, 72. Upon the rear shaft 36 are keyed the rear fans 17, 130

17' and the sprocket wheel 51 over which the chain belt 12 runs. Upon the front shaft 37 are keyed the front fans 18, 18' and the sprocket wheel 50 over which the chain belt 5 13 runs.

The arms or spokes 44, 44, the blades or paddles 45, 45, the disks 42, 42, the key and key seat 43, the cross-pieces 52, 52, the dead center belts 21, 21 in connection with the 10 shafts 36, 37 constitute the fans, 17, 17', 18, 18'. The dead center belts serve to keep the air in front from the center of the fans. The holes for the shafts 36, 37 are bored through the center of the disks 42, 42 and 15 through the middle of the arms 44, 44. The key seats 43, 43 are cut in the faces of the disks 42, 42 and in such manner that keys passing across the centers of the shaft through key holes may be lodged in said 20 key seats. The arms 44, 44, in pairs are let half and half into each other at their middles. Gains or notches 46, 46, are cut in the corners of said arms to receive the blades or paddles 45, 45, which are secured in the 25 gains on opposite sides of and at the ends of the arms, 44, 44. The cross-pieces 52, 52 are secured to the arms 44, 44 near the blades 45, 45. The dead center belts 21, 21 may be made of lumber extended from cross-piece 30 52 to cross-piece 52 and secured to the cross-pieces and to said arms, or the dead center belts may be made of canvas or leather carried over the cross-pieces 52, 52, and the ends of the belts laced together. The object 35 of the dead center belts is to prevent the air in front of the fans from rushing in to the center of the fans. In mounting the fans on the shafts, the shafts 36, 37 are passed through the annular ball bearings 38, 38, 40 and through the shaft holes in the arms 44, 44 and through two disks 42, 42 for each fan. Then the keys are inserted in the key holes in said shafts and said disks brought against the keys so that the keys will be in the key 45 seats 43, 43 cut in the faces of said disks. Then said disks are securely bolted with bolts and nuts to said arms 44, 44 with the keys pinched between the disks and the arms. Then the thrust ball bearings 39, 39 are 50 placed on the ends of said shafts and secured in position by means of the threads on the ends of said shafts and the nuts 73, 73.

The compartments 77, 83 on the left side and 81, 89 on the right side of the air-ship 55 may be closed up on the sides of said compartments and in the rear and above, but not in front below the deflectors 24, 25 nor on the bottom, with canvas or other suitable material.

60 In the half cylinders or half barrel shaped devices 23, 23 constructed behind and over the fans 17, 17', 18, 18' respectively, the full width of the respective fans, the hoops 53 with the canvas 54 stretched over them are 65 secured to the cross-pieces 48, 48 which in

turn are secured to the frame of the air-ship.

In the front deflector 25 braces 78 are secured to the deflector posts 47, 47 and to the front posts 34, 34 of the body of the air-ship, and to the frame of the aeroplane, and 70 canvas is stretched across and on the under side of said braces and secured to them and to the cross-pieces 48, 48.

In the rear deflectors 24, braces 79 are secured to the front posts of the compartments 75 77, 89, and to the frame of the aeroplane, and canvas is stretched across and on the under side of said braces 79 and secured to them and to the cross-pieces 48.

I apply the principle that effective work 80 can be had in lifting and propelling an air-ship by means of vertical revolving paddle fans, when the effective work accomplished in one half of each revolution of the fans is not neutralized by the work done in the 85 other half of each revolution of the fans by means of the device whereby the downward and rearward strokes of the paddles of the vertical revolving fans are made in the free open air and the upward and forward 90 strokes are made within the body of the air-ship or within half cylinders or half barrel shaped devices secured to the sides of the air-ship or within compartments constructed on the sides of the air-ship open in front and 95 below and closed up behind and above the fans and wholly or partially closed up on the sides. The principle that more effective work is performed by two wind fans or wind propellers where each of them operates in 100 air undisturbed by the other I apply by placing the rear fans not directly behind the front fans.

By placing the vertical revolving propeller-lifting fans fore and aft, on both sides 105 of the air-ship, so that the burden to be carried in the center of the air-ship and below the plane of the shafts carrying the fans will be carried between the fans the liability of the air-ship to tip sidewise or endwise is 110 greatly lessened.

I do not claim the aeroplane, the ground wheels, the means by which the front ground wheel is steered, the means by which the rear ground wheel is made to revolve, the 115 motor, the gearing, the rudders, the fans nor the dead center belts as distinct elements.

I claim:

1. In an air-ship the combination, substantially as shown and specified, of an aeroplane, the body portion of the air-ship embodying a central longitudinal section and on opposite sides thereof, side longitudinal sections, the stem or prow on the front end of said central longitudinal section, adapted to cleave the air and deflect it to the exposed fronts of the propelling-lifting fans, ground wheels adapted to support the body portion of the air-ship, means for driving rear ground wheel, means for steering front 120 125 130

- 4
- wheel, vertical rudders adapted to swing on hinged joints on the rear corners of the body portion of the air-ship for steering and stopping the air-ship, means for controlling said 5 rudders, motor adapted to actuate the shafts of the propelling-lifting machine, and a propelling-lifting machine, comprising front and rear shafts, installed in the body portion of the airship at right angles to the vertical 10 plane of the longitudinal axis of the airship, the bearings in which said shafts are installed, suitable gearing connecting said shafts with the motor, two propelling-lifting fans mounted in opposite sides of the body 15 portion of the air-ship on said front shaft and adapted to revolve with it forward and downward, two propelling-lifting fans mounted in opposite sides of the body portion of the air-ship on said rear shaft and adapted 20 to revolve with it forward and downward, front and rear deflectors adapted to deflect air to the exposed fronts of said fans and to force the airship upward and fan 25 hoods or partially inclosed fan compartments in the nature of hoods for said fans.
2. In an air-ship the combination, substantially as shown and specified, of an aeroplane, the body portion of the air-ship embodying a central longitudinal section and on opposite sides thereof side longitudinal sections, the stem or prow on the front end of said central longitudinal section adapted to cleave the air and deflect it to the exposed 30 fronts of the propelling-lifting fans, vertical rudders adapted to swing on hinged joints on the rear corners of the body portion of the airship for steering and stopping the air-ship, means for controlling said rudders, motor adapted to actuate the shafts of 35 the propelling-lifting machine, and a propelling-lifting machine, comprising front and rear shafts installed in the body portion of the air-ship at right angles to the vertical 40 plane of the longitudinal axis of the air-ship, the bearings in which said shafts are installed, suitable gearing connecting said shafts with the motor, two propelling-lifting fans mounted in opposite sides of the body portion of the air-ship on said front shaft and adapted to revolve with it, forward and downward, two propelling-lifting fans mounted in opposite sides of the body portion of the air-ship on said rear shaft and adapted to revolve with it, forward and downward, front and rear deflectors 45 adapted for forcing the air-ship upward and to deflect air to the exposed fronts of the fans and fan hoods or partially inclosed fan compartments in the nature of hoods for 50 said fans.
3. In an air-ship, the combination substantially as shown and specified of the body portion of the air-ship embodying a central longitudinal section and on opposite sides thereof side longitudinal sections, the longitudinal roof timbers of the body portion of the air-ship projected in front of the airship, adapted to form junctions with the forward ends of the front deflectors, the stem or prow on said central section adapted 55 to cleave and deflect the air to the exposed fronts of the propulsion fans, vertical rudders adapted to swing on hinged joints on the rear corners of the body portion of the air-ship for steering and stopping the air-ship, means for controlling said rudders, motor adapted to actuate the shafts of the propelling-lifting machine, and a propelling-lifting machine comprising front and rear shafts mounted in the body of the airship at right angles to the vertical plane of the longitudinal axis of the air-ship, the bearings in which said shafts are installed, suitable gearing connecting said shafts with the motor, two propelling-lifting fans 60 mounted in opposite sides of the body portion of the air-ship on said front shaft and adapted to revolve with it, forward and downward, two propelling-lifting fans mounted in opposite sides of the body portion of the air-ship on said rear shaft and adapted to revolve with it, forward and downward, front and rear deflectors, adapted for forcing the air-ship upward and to deflect air to the exposed fronts of the fans, and fan hoods or partially inclosed compartments in the nature of fan hoods for said fans.
4. In an air-ship the combination substantially as shown and specified of the body portion of the air-ship embodying a central longitudinal section and on opposite sides thereof side longitudinal sections, the longitudinal roof timbers of the body portion of the air-ship projected in front of the airship, adapted to form junctions with the forward ends of the front deflectors, the stem or prow on said central section adapted to cleave and deflect the air to the exposed fronts of the propulsion fans, vertical rudders adapted to swing on hinged joints on the rear corners of the body portion of the air-ship for steering and stopping the air-ship, means for controlling said rudders, motor adapted to actuate the shafts of the propelling-lifting machine, and a propelling-lifting machine comprising front and rear shafts mounted in the body of the airship at right angles to the vertical plane of the longitudinal axis of the air-ship, the bearings in which said shafts are installed, suitable gearing connecting said shafts with the motor, two propelling-lifting fans 65 mounted in opposite sides of the body portion of the air-ship on said front shaft and adapted to revolve with it, forward and downward, two propelling-lifting fans mounted in opposite sides of the body portion of the air-ship on

said rear shaft and adapted to revolve with it forward and downward, front and rear deflectors adapted for forcing the air-ship upward and to deflect air to the exposed 5 fronts of the fans, and fan hoods or partially inclosed compartments in the nature of hoods for said fans.

5. In an air-ship, the combination substantially as shown and specified of an aeroplane, the body portion of the airship, motor adapted to actuate the shafts of the propelling-lifting machine, and a propelling-lifting machine, comprising front and rear shafts installed in the body portion of the 10 air-ship at right angles to the vertical plane of the longitudinal axis of the air-ship, bearings in which said shafts are mounted, suitable gearing connecting said shafts with the motor, two propelling-lifting fans 15 mounted in opposite sides of the air-ship on said front shaft and adapted to revolve with it forward and downward, two propelling-lifting fans mounted in opposite sides of the air-ship on said rear shaft and adapted 20 to revolve with it forward and downward, and fan hoods or partially inclosed compartments in the nature of hoods for said fans.

6. In an air-ship, the combination substantially as shown and specified of the body portion of the air-ship, motor adapted to actuate the shafts of the propelling-lifting machine, and a propelling-lifting machine comprising front and rear shafts installed 30 in the body portion of the air-ship at right angles to the vertical plane of the longitudinal axis of the air-ship, the bearings in which said shafts are mounted, suitable gearing connecting said shafts with the 35 motor, two propelling-lifting fans mounted in opposite sides of the air-ship on said front shaft and adapted to revolve with it forward and downward, two propelling-lifting fans mounted in opposite sides of the 40 air-ship on said rear shaft and adapted to revolve with it forward and downward, and fan hoods or partially inclosed compartments, in the nature of hoods for said fans.

7. In an air-ship, the combination substantially as shown and specified of an aeroplane, the body portion of the air-ship, embodying a central longitudinal section and on opposite sides thereof side longitudinal sections, stem or prow on front end of said 55 central longitudinal section adapted to cleave the air and deflect it to the exposed fronts of the propelling-lifting fans, ground wheels adapted to support the body portion of the air-ship, means for driving the rear 60 ground wheel, means for steering the front ground wheel, vertical rudders adapted to swing on hinged joints on the rear corners of the body portion of the air-ship for steering and stopping the air-ship, means for 65 controlling said rudders, front and rear

shafts installed in the body of the air-ship at right angles to the vertical plane of the longitudinal axis of the air-ship, the bearings in which said shafts are installed, means for actuating said shafts, propelling-lifting 70 fans mounted on said shafts in opposite sides of the air-ship, adapted to revolve with said shafts forward and downward, front and rear deflectors adapted to forcing the air-ship upward and to deflect air to the exposed 75 fronts of the fans and fan hoods or partially inclosed compartments in the nature of fan hoods adapted to the forward parts and a portion of the upward parts of said fans' revolutions being made within 80 said hoods or fan compartments.

8. In an air-ship, the combination substantially as shown and specified of the body portion of the air-ship, front and rear shafts installed in the body of the air-ship at right 85 angles to the vertical plane of the longitudinal axis of the air-ship, the bearings in which said shafts are installed, means for actuating said shafts, two propelling-lifting fans mounted on said front shaft in opposite sides of the air-ship, two propelling-lifting fans mounted on said rear shaft in opposite sides of the air-ship over to the sides of and not directly in the rear of said front fans and thereby adapted to operate in air 90 substantially undisturbed by said front fans, said propelling-lifting fans being adapted to revolve with the shafts upon which they are respectively mounted forward and 95 downward, fan hoods or compartments partially inclosed in the nature of fan hoods, adapted to the forward parts and to a portion of the upward parts of said fans' revolutions being made within said hoods or fan compartments.

9. In an air-ship the combination substantially as shown and specified of the body portion of the air-ship embodying a central longitudinal section and on opposite sides thereof side longitudinal sections, front and rear shafts installed in the body of the air-ship at right angles to the vertical plane of the longitudinal axis of the air-ship, the bearings in which said shafts are installed, means for actuating said shafts, two propelling-lifting fans mounted on said front shaft in opposite sides of the air-ship, two propelling-lifting fans mounted on said rear shaft in opposite sides of the air-ship, each of said fans comprising two or more pairs 100 of radial and parallel cross-arms, having paddle blades at the extremities of each pair of cross-arms, set parallel to the shaft upon which the fan is mounted, dead center belts between the successive pairs of cross-arms, 105 thereby forming a belt extending around each fan at the inner edges of the paddle blades adapted to drive the air outward from the center of the fans, means by which said fans are secured to the shafts, said fans being 110 115 120 125 130

adapted to revolve with the shafts upon which they are respectively mounted forward and downward, fan hoods or partially inclosed compartments in the nature of fan hoods constructed in the body portion of the air-ship, inclosed in the rear ends, tops and on the right and left sides and open on the

under sides and in the front ends except short spaces at the tops of the front ends, which short spaces are inclosed.

JOHN MUCKLE.
